UNITED STATES PATENT OFFICE.

HENRY L. BARTON, OF PITTSBURG, PENNSYLVANIA, ASSIGNOR TO THE WESTINGHOUSE MACHINE COMPANY, A CORPORATION OF PENNSYLVANIA.

BLADE-HOLDING MEANS.

940,778.

Specification of Letters Patent. Patented Nov. 23, 1909.

Application filed May 14, 1907, Serial No. 373,667. Renewed April 20, 1908. Serial No. 428,146.

To all whom it may concern:

Be it known that I, HENRY L. BARTON, a citizen of the United States, and a resident of Pittsburg, in the county of Allegheny and State of Pennsylvania, have made a new and useful Invention in Blade-Holding Means, of which the following is a specification.

This invention relates to elastic fluid turbines, and more particularly to blade and vane securing means therefor.

In the construction of elastic fluid turbines, and more particularly in those in which alternate annular rows of stationary vanes and moving blades are employed, various means have been utilized for securing the blades and vanes to their respective holding elements. In one method which has been employed to a large extent the holding elements, such as the turbine stator and rotor, are circumferentially grooved; the grooves are undercut; the blades or vanes are secured to a base strip; the base strip inserted within the groove, and a calking strip, inserted between one wall of the groove and the base strip, is expanded transversely of the groove. This method is more or less satisfactory, but, owing to the fact that blading strips occur and that it becomes necessary to reblade machines in the field, it has been found that the reblading of turbines in which the blades are mounted as in the method described is not only difficult but unsatisfactory.

An object of this invention has been to produce improved means for securing blade and vane sections (a section consists of a number of blades or vanes secured or attached to a base strip or section) to their respective holding elements.

In the drawings accompanying and forming a part of this application; Figure 1 is a developed section of a portion of a turbine blade or vane holding element provided with a circumferentially extending undercut groove or slot in which is located a blade section secured to the holding element in accordance with this invention; Fig. 2 is an end elevation taken on the line A—A of Fig. 1; Fig. 3 is an end elevation taken on the line B—B of Fig. 1; Fig. 4 is a view in perspective of two complementary wedges entering into this invention; Fig. 5 is a view in perspective of a modified form of wedge

entering into this invention; and Fig. 6 is an end elevation of a blade or vane holding element, a blade section and complementary wedges formed in accordance with the modification illustrated in Fig. 5.

In carrying the invention into practice a turbine blade or vane holding element 7 is circumferentially grooved and the groove is undercut on both sides, as shown at 8 and 9 in Figs. 2 and 3; or as shown in Fig. 6, undercut on but one side. A blade section 65 consisting of a base ring or strip 10 cut into the desired lengths and provided with blades or vanes 11 secured thereto in any suitable manner is inserted in one of the grooves. The grooves are of such width that a slot 70 is provided between wall 9 of the groove and side 12 of the base ring, and at one or more points along the groove the same is widened as shown at 13, Fig. 1. As shown in Figs. 1, 2 and 3, double or compound tapered complementary wedges 14 are singly inserted in the notched portions of the groove 13, slid around within the slot and driven home so as to securely bind and lock the blade sections within the grooves. The pairs of wedges may abut one against another, leaving the widened space 13 open, into which a malleable metal filler may be calked, thus locking all of the wedges together, or spaces may be left between the several pairs of wedges and the metal of the holding element peened over so as to engage with slots 15 formed in the top sides of the wedges.

When it is desired to remove the blade sections for any reason, or the base rings after the blades have been stripped therefrom by accident, the wedges may be loosened by engaging a suitable tool with the wedges in the slots 15. When the wedges are thus loosened they may be moved around to the widened openings and through them removed.

If it is desired, the wedges need not have a double taper but may be formed as shown in Figs. 5 and 6 with a bead 16 formed on one side and a groove 17 on the other. When wedges of this character are used the base ring will be provided with a bead 18 as shown in Fig. 6 and one wall of the groove in the holding element will be formed with a groove to receive the bead 16.

It will be understood that since this in-

vention is generic many modifications may be made from the construction shown without departing from the spirit of this invention.

5. Having thus described my invention, what I claim as new and useful and desire to secure by Letters Patent is:

1. In combination with a turbine blade or vane holding element provided with a circumferential groove or channel, a turbine blade or vane base ring located in said channel, and complementary wedges located between said base ring and one wall of said channel.

15. 2. In combination with a turbine blade or vane holding element provided with a circumferential groove or channel, a turbine blade or vane base ring located in said channel, and a plurality of wedges located between said base ring and one wall of said channel.

25. 3. In combination with a turbine blade or vane holding element provided with a circumferential groove or channel, a turbine blade or vane base ring located in said channel, and double tapered wedges located between said base ring and one wall of said channel.

30. 4. In combination with a turbine blade or vane holding element provided with a circumferential groove or channel, a turbine blade or vane base ring located in said channel, and compound wedges located between said base ring and one wall of said channel.

35. 5. In combination with a turbine blade or vane holding element provided with a circumferential groove or channel, a turbine blade or vane base ring located in said chan-

nel, and a wedge located between said base ring and one wall of said channel.

6. In combination with turbine blade or vane sections, wedges securing said sections to their respective holding elements.

7. In combination with the blade holding element of a turbine, a blade mounting slot provided in said element, a plurality of blades located within said slot and means, comprising complementary wedges, located within said slot for securing said blades in place.

40. 8. In combination with a blade holding element of a turbine, a blade mounting slot provided within said element, a plurality of blades mounted in said slot and means, comprising compound complementary wedges, for securing said blades in place.

45. 9. In combination with the blade holding element of a turbine, a blade mounting slot provided in said element, a plurality of blades located within said slot and means, comprising a plurality of wedges, for securing said blades in place within said slot.

50. 10. In combination with the blade holding element of a turbine, a blade mounting slot provided therein, a plurality of blades located within said slot, means for spacing the bases of said blades and means, comprising complementary wedges, for securing said blades in place.

55. In testimony whereof, I have hereunto subscribed my name this 13th day of May, 1907.

HENRY L. BARTON.
